(57) **CLAIM**

The ornamental design for a child resistant tamper evident side open zipper bag, as shown and described.

DESCRIPTION

FIG. 1 is a first isometric view of the child resistant tamper evident side open zipper bag showing my new design;

FIG. 2 is a second isometric view thereof;

FIG. 3 is a front view thereof;

FIG. 4 is a back view thereof;

FIG. 5 is a left side view thereof;

FIG. 6 is a right side view thereof;

FIG. 7 is a top plan view thereof; and,

FIG. 8 is a bottom plan view thereof.

The broken lines in the drawing depict environmental subject matter only and form no part of the claimed design.

1 Claim, 8 Drawing Sheets
